UNITED STATES PATENT OFFICE.

SETH H. HEFT, OF DETROIT, MICHIGAN, ASSIGNOR TO THE PRESSED STEEL EQUIPMENT COMPANY, OF CHICAGO, ILLINOIS, A CORPORATION OF ILLINOIS.

DUST'GUARD.

1,232,305.

Specification of Letters Patent.

Patented July 3, 1917.

Application filed February 19, 1917. Serial No. 149,479.

To all whom it may concern:

Be it known that I, SETH H. HEFT, a citizen of the United States, residing at Detroit, in the county of Wayne and State 5 of Michigan, have invented a certain new and useful Improvement in Dust-Guards, of which the following is a full, clear, concise, and exact description.

This invention relates to dust guards and 10 more particularly to dust guards of the type designed for use in connection with railway car axle journal boxes.

In the present state of the art, the dust guard commonly used with the standard 15 construction of railway journal boxes, is a wooden plate apertured for the insertion of the axle, said wooden plate being positioned within the usual dust guard housing forming a part of the journal box. To permit 20 of the insertion of the axle into the journal box, it is necessary to provide a clearance in the guard. The guard, when placed in service, does not therefore form a close fit. Furthermore, as the bearing wears, the box 25 will be lowered in relation to the axle which will enlarge the clearance at the bottom of the guard. Thus at no time is a guard of such construction, strictly speaking, a dust guard, since the clearance is sufficient for 30 the entrance of dust and grit, which materially shortens the life of the journal bearing. Much difficulty has also been experienced by reason of the fact that the wooden plates oftentimes become cracked or broken 35 when in use, thereby rendering them useless in the performance of their functions. Notwithstanding these disadvantages, however, it has been found highly desirable to use wood in the construction of dust guards of 40 this type.

It is therefore the primary object of the present invention to overcome these various disadvantages and to provide a dust guard of the type described, wherein the wooden 45 member is adapted to be clamped closely about the axle at all times, thereby preventing the admission of dust and grit into the journal box.

A further object of the invention resides 50 in the provision of suitable means adapted to coöperate with the wooden member, whereby the durability of the same is increased, and whereby a snug fit between said wooden member and the car axle is maintained, regardless of cracks or breaks therein.

A still further object of the invention is the provision of a dust guard which shall be self-adjusting and which shall be provided with means adapted to compensate for any wear which may be occasioned by 60 the frictional contact of the wooden member with the axle.

Other objects and advantages will be apparent from the following description, taken in connection with the accompanying drawings, wherein the preferred embodiment of 65 the invention is illustrated:

In the accompanying drawings:

Figure 1 is a vertical longitudinal sectional view taken through a journal box 70 of standard construction, showing the dust guard applied to the car axle.

Fig. 2 is a vertical transverse sectional view thereof.

Fig. 3 is a cross sectional view of the dust 75 guard.

Fig. 4 is a side elevation; and

Fig. 5 is a front view of a modified form of the wooden member.

In the drawings, a journal box of stand- 80 ard construction is illustrated at A, the dust guard housing being shown at B and being provided with the usual closure C. D designates a portion of the car axle shown in position in the journal box.

The dust guard is shown mounted within 85 the housing B and in operative position on the car axle, said guard being provided with a ring 10, preferably constructed of wood, which is adapted to closely fit about the 90 circumference of said axle. This wooden ring 10 is shown split at 11 along a line substantially tangent to the circumference of the axle, it being obvious however that any other desirable form of joint may be 95 employed. The abutting ends of the split wooden ring 10 are retained in proper alignment by means of a suitable clip 12, which may be fastened in any preferred manner to one of said abutting ends, said clip being adapted to slidably engage the other of 100 said ends to aid in the self-adjustment of said ring about the axle, as hereinafter pointed out.

Encircling the wooden ring 10 is a resil- 105 ient U-shaped band 13, which is preferably channeled as at 14 to receive the outer surface of the ring 10, said resilient band 13 being provided with arms 15 which are shown projecting slightly above the upper 110

edge of the ring 10 at 16. The upper edge of said ring 10 is cut away adjacent to the projecting ends 16, as shown at 17, to permit of said ends being easily accessible for 5 the purpose hereinafter pointed out. These projecting ends 16 provide suitable grips whereby said channeled band 13 may be expanded or sprung out of its normal position to permit of the insertion of the wooden ring 10 between the arms 15 and into the channel 14 of said band 13, said projecting ends 16 also serving as means whereby the abutting ends of the ring 10 may be separated, thereby increasing the diameter of said ring 10 to permit of the axle being passed therethrough.

The wooden ring 10 is adapted to seat well down into the channel of the band 13 substantially as shown. This not only provides 20 the necessary resilient strength which retains the split ring 10 closely fitted about the axle, but also provides a reinforcement for said ring, which protects the periphery thereof and also a substantial portion of the opposite faces thereof. Thus the durability of 25 the wooden ring is greatly increased, and said ring is protected against cracking and breaking due to rough usage. It will be noted however, that even though the wooden 30 ring should become cracked or broken, the channeled band 13, constructed and applied to said ring as above set forth, will retain the same in operative position.

In applying the dust guard to an axle 35 after it has been assembled, as shown in Fig. 2, and in the manner above pointed out, said dust guard is placed within the housing B of the journal box A, the projecting ends 16 of the resilient band 13 being then gripped 40 and sprung apart, which action also separates the abutting ends of the wooden ring 10, by virtue of its being held within the channelled portion of said band. This permits of the insertion of the car axle through 45 the dust guard, after which the ends 16 are released and the tension of the resilient band 13 forces the abutting ends of the ring together, thus closely fitting said ring about the axle. It will be noted that the close fit 50 between the dust guard and the axle will have a tendency to cause said guard to turn with said axle. This rotation of the dust guard with the axle is prevented however by the arms 15 coming into contact with the 55 wall of the dust guard housing, thereby holding said dust guard stationary with relation thereto. As the axle thus revolves within the ring 10, a gradual wearing away of the inner surface thereof is caused. It 60 will be noted however, that this gradual wearing away is compensated for by the resilient band 13, the tension exerted thereby causing the abutting ends of said ring 10 to slide one over the other, thus contracting 65 said ring as it is worn, and tending to retain

the same in close engagement with the axle at all times. From this, it will be noted that all dust and grit is prevented from working in between the axle and the wooden ring 10, and that a dust guard has been provided 70 which is self-adjusting and which is adapted to compensate for any wearing occasioned by the frictional contact between the inner surface of the wooden ring 10 and the car axle.

If, under some conditions, it proves difficult to spring the wooden ring 10 sufficiently to position said ring about the axle without breaking the same or otherwise injuring it, said ring may be cut radially at intervals as 80 shown in Fig. 5, to permit the abutting ends of said ring being separated an appreciable amount, when the same is being placed in position on the axle. The ring may be cut part-way through as shown, or all the way 85 through, if desired.

It is obvious that various changes and modifications may be made in the construction illustrated herein, without departing from the spirit of the invention, and the 90 right is therefore reserved to make such changes and modifications as fairly fall within the scope of the appended claims.

Having thus described my invention, what I claim as new and desire to secure by Letters Patent of the United States is:

1. A dust guard of the type described, comprising a split wooden ring adapted to closely fit an axle, and a channeled resilient band adapted to embrace said ring to reinforce the same.

2. A dust guard of the type described, comprising a split wooden ring adapted to closely fit an axle, and a channeled resilient band adapted to embrace said ring to reinforce the same, said band affording means whereby the abutting ends of said wooden ring may be separated to permit of the insertion of an axle therethrough.

3. A dust guard for journal boxes, comprising a split wooden ring, a resilient metal band adapted to fit said ring and to press the inner surface thereof into close contact with an axle, said ring being provided with flanges adapted to embrace the sides thereof 115 to reinforce said ring and to prevent the same being rendered inoperative by cracks or breaks.

4. A dust guard for journal boxes, comprising a split wooden ring, a channeled resilient metal band adapted to embrace said ring to reinforce the same, and to press the inner surface thereof into close contact with an axle, the ends of said band projecting above the upper edge of said ring to afford 120 means for expanding the same when the guard is positioned on an axle.

5. A dust guard for journal boxes, comprising a split wooden ring, a channeled band adapted to embrace the same and to 125

retain it in close contact with an axle, the ends of said band being projected above one edge of said ring to provide means whereby said band may be expanded.

- 5 6. A dust guard of the type described, comprising a split wooden ring and a U-shaped channelled resilient band adapted to embrace said ring to reinforce the same and to hold the same closely fitted about an axle.
- 10 7. A dust guard for journal boxes, comprising a split wooden ring, a channelled U-shaped band adapted to embrace said ring to reinforce the same, the upper portion of said ring being held between a plurality of converging arms forming a part of said U-shaped band, said arms affording means
- 15

whereby said band may be sprung to permit of said guard being positioned on an axle.

8. A dust guard for journal boxes, comprising a split wooden ring, a channelled U-shaped band adapted to embrace said ring to reinforce the same, the upper portion of said ring being held between a plurality of converging arms forming a part of said U-shaped band, and a clip positioned intermediate said arms and adapted to coöperate with the adjacent ends of said ring to retain the same in proper alinement. 20 25

In witness whereof, I, hereunto subscribe my name this 2nd day of Feby. A. D., 1917. 30

SETH H. HEFT.
